United States Patent Office.

GEORGE ALVAN KNOWLTON, OF NATICK, MASSACHUSETTS.

Letters Patent No. 71,887, dated December 10, 1867.

IMPROVEMENT IN OIL-CANS.

The Schedule referred to in these Letters Patent and making part of the same.

TO ALL WHOM IT MAY CONCERN:

Be it known that I, GEORGE ALVAN KNOWLTON, of Natick, in the county of Middlesex, and State of Massachusetts, have invented a new and useful Improvement in Oil-Cans; and I do hereby declare the following to be a full, clear, and exact description of the same, reference being had to the accompanying drawing, which is made a part of this specification.

In this oil-can the spout is closed by a stopper, to prevent evaporation, as is also the tube or ventage which supplies air to the can to avoid a vacuum and insure the free flow of the oil when the spout-stopper is retracted to permit the oil to be poured out for use. The ventage-stopper is depressed or retracted in the act of retracting the spout-stopper, which is effected by pressure upon a rod working through the ventage-tube, the stoppers being forced into their closing positions by the action of spiral springs arranged as hereinafter described.

The drawing is a vertical section of an oil-can, illustrating my invention.

A may represent an oil-can closed at top by a closely-fitting cap or stopper, B, which may be provided with a suitable packing material B, to make an air-tight joint. C is the spout, and C' its nozzle, through which the oil is poured from the can. The shoulder c, around the internal orifice of the nozzle C', forms a bearing for the elastic stopper D, whose supporting-rod E is jointed to an arm, F, which is hinged at f to the inside of the can A. A spiral spring, G, drawing upward the free end of the arm F, serves to force the stopper D against the shoulder c, and thus close the spout and prevent the oil from evaporating or leaking through the same. H is a rod united to the arm F, and carrying an elastic stopper, I, for closing the ventage-tube K, through which the rod H projects, as shown. The outer end of the rod H is in convenient proximity to the handle A', and is provided with a disk or thumb-piece, h'. By depressing the rod H the stoppers D I are simultaneously depressed or retracted from their respective orifices, thus permitting oil to be poured out through the spout and admitting air to the interior of the can through the tube K. The air thus admitted prevents the occurrence of a vacuum, and insures the free outward flow of the oil. h is a disk, fixed rigidly upon the rod H, and forming an abutment for a spring, J, which exerts an independent pressure upon the stopper I, the better to retain it in its closing position. The spring J, while keeping the stopper I closed, allows a sufficient play of the arm F to insure the complete closure of the stopper D by the spring G. It will be seen that the position of the trigger H h' enables it to be actuated with the greatest ease in the act of tilting the can to pour out the oil. Thus the thumb of the hand which grasps the handle A' is placed upon the disk h', and the pressure exerted upon h' in order to tilt the can, serves also to actuate the stoppers. This is a feature of great practical utility.

Having described my invention, what I claim as new, and desire to secure by Letters Patent, is—

1. The stoppers D and I, retracted from their respective orifices by a single trigger, H h', and provided with two springs G, J, to insure the effective closure of both said orifices, substantially as described.
2. In a valved oil-can, constructed as above specified, I further claim the arrangement of the trigger H h' obliquely on the upper side of the handle A', as and for the purpose set forth.

To the above specification of my improvement in oil-cans, I have signed my hand, this 14th of September, A. D. 1867.

G. A. KNOWLTON.
